US0D1112958S

(12) United States Design Patent (10) Patent No.: US D1,112,958 S
(45) Date of Patent: * Feb. 10, 2026

(54) LIFE JACKET

(71) Applicant: Troy Faletra, Fort Lauderdale, FL (US)

(72) Inventor: Troy Faletra, Fort Lauderdale, FL (US)

() Term: 15 Years

(21) Appl. No.: 29/903,548

(22) Filed: Sep. 25, 2023

(51) LOC (15) Cl. 29-02

(52) U.S. Cl.

USPC D21/805; D29/101.4

(58) Field of Classification Search

(57) CLAIM

The ornamental design for a life jacket as shown and described.

DESCRIPTION

FIG. 1 is a perspective view of a life jacket showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The evenly dashed broken lines in the drawings depict stitching and do form part of the claimed design. The long dash/short dash lines in the drawings depict portions of the life jacket that form no part of the claimed design.

1 Claim, 7 Drawing Sheets
